[57] CLAIM

The ornamental design for a trailer roller, as shown and described.

DESCRIPTION

FIG. 1 is a perspective view of a trailer roller incorporating my design;

FIG. 2 is a side elevation view thereof, the opposite side being a mirror image of that shown; and,

FIG. 3 is a front elevation view thereof, the rear view being a mirror image of that shown.

FIG. 1

FIG. 2

FIG. 3
